CLAIM

The ornamental design for a television receiver, as shown and described.

DESCRIPTION

FIG. 1 is a front perspective view of the television receiver showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a back perspective view thereof;

FIG. 9 is a reference view showing the state of use that the front display part of the claimed design is being raised;

FIG. 10 is a front perspective view in a condition that the front display part of the claimed design has been raised;

FIG. 11 is a front view of FIG. 10;

FIG. 12 is a back view of FIG. 10;

FIG. 13 is a left side view of FIG. 10;

FIG. 14 is a right side view of FIG. 10;

FIG. 15 is a top plan view of FIG. 10;

(Continued)

FIG. 16 is a bottom plan view of FIG. 10;
FIG. 17 is a back perspective view of FIG. 10;
FIG. 18 is reference view showing the state of use that the front display part of the claimed design is being rotated;
FIG. 19 is a front perspective view in a condition that the front display part of the claimed design has been rotated 90 degrees;
FIG. 20 is a front view of FIG. 19;
FIG. 21 is a back view of FIG. 19;
FIG. 22 is a left side view of FIG. 19;
FIG. 23 is a right side view of FIG. 19;
FIG. 24 is a top plan view of FIG. 19;
FIG. 25 is a bottom plan view of FIG. 19;
FIG. 26 is a back perspective view of FIG. 19;
FIG. 27 is a reference view showing the state of use that the front display part of the claimed design is being pushed downward;
FIG. 28 is a front perspective view in a condition that front display part of the claimed design has been pushed downward;
FIG. 29 is a front view of FIG. 28;
FIG. 30 is a back view of FIG. 28;
FIG. 31 is a left side view of FIG. 28;
FIG. 32 is a right side view of FIG. 28;
FIG. 33 is a top plan view of FIG. 28;
FIG. 34 is a bottom plan view of FIG. 28; and,
FIG. 35 is a back perspective view of FIG. 28.

The broken lines depict portions of the television receiver that form no part of the claimed design.

1 Claim, 35 Drawing Sheets
